UNITED STATES PATENT OFFICE.

ERNST PAUL RIESSNER, OF WAHREN, GERMANY.

MUSIC-BOX.

No. 878,088.

Specification of Letters Patent.

Patented Feb. 4, 1908.

Application filed July 21, 1905. Serial No. 270,671.

To all whom it may concern:

Be it known that I, ERNST PAUL RIESSNER, a subject of the Emperor of Germany, and a resident of Wahren, near Leipzig, 5 Kingdom of Saxony, and Empire of Germany, have invented certain new and useful Improvements in Music-Boxes, of which the following is a specification.

My invention relates to music boxes, and 10 particularly to an arrangement whereby the driving mechanism of a music box may be utilized for operating a talking machine record.

My present invention has for its object 15 to provide a very simple construction for the above indicated purpose, which will permit of using the same machinery for the purpose of regulating the speed, either of the customary note-disk or of the talking machine 20 record.

The features of my invention will appear from the description hereinafter following and from the appended claims.

Reference is to be had to the accompanying drawings, in which

Figure 1 is a plan of a music box embodying my invention illustrated in condition for use as a talking machine; Fig. 2 is a sectional elevation on line 2—2 of Fig. 3; Fig. 3 30 is a sectional plan on line 3—3 of Fig. 2; Fig. 4 is a plan view showing another form of my invention; Fig. 5 is a horizontal section of the same; Fig. 6 is an elevation with parts in section substantially on line 6—6 of Fig. 5; Fig. 7 is a sectional elevation on line 7—7 of 35 Fig. 6; and Fig. 8 is an enlarged detail section on line 8—8 of Fig. 3; and Fig. 9 is an elevation thereof looking from the right of Fig. 8.

40 A indicates the box containing the mechanism, and also serving to support in any suitable manner the horn B and the arm C carrying the reproducer D. These parts may be of any suitable construction. The 45 reproducer is adapted to rest on the record E carried by a rotary supporting plate F and adapted to be rotated thereby so as to reproduce music, song or speech in the customary manner. The supporting plate F is provided with a central downward projection F', 50 having a clutch connection with a projection G' upon a shaft G, which is one of the shafts of the music box motor. The clutch connection in the particular instance illustrated 55 is formed by providing the lower end of the

projection F' with a conical seat and by tapering the upper end of the projection G' correspondingly. The shaft G carries a worm-wheel G² engaging a worm H' on the shaft H, which also carries the governor H². 60 Furthermore, the governor-shaft has a projection H³, into the path of which normally projects a stop I. This stop is mounted on a shaft I', adapted to be rocked by means of a slide I² engaging an arm I³ on the shaft. A 65 spring I⁴ keeps the arm I³ against the slide I². There is also provided a speed regulator, consisting of an arm H⁴, pivoted at H⁶ and provided with a beveled portion H⁸ which is adapted to engage a brake member a secured 70 to an arm b pivoted at c to a stationary portion of the instrument and maintained in its normal position by a spring d. The brake member a is provided with a pad of felt or like material adapted to frictionally 75 engage the disk H⁵ of the governor. By pressing down a handle H⁷, the arm H⁴ will be rocked on its pivot H⁶ so that the beveled portion H⁸ will be swung upward and will move the brake member a toward the 80 disk H⁵ against the tension of the spring d. The pad will thus engage the surface of the disk H⁵ and will act as a brake to regulate the speed of the instrument. It will be understood that by moving the stop I out of 85 the path of the projection H³, the mechanism of the music box is released.

The shaft G is also provided with a pinion G³ engaging a gear-wheel J' on a shaft J, which also carries a pinion J². This pinion 90 meshes with a gear-wheel K' on a shaft K, which gear-wheel is also in mesh with a spur-gear L' on the spring drum L. This spring drum is also formed with teeth L² upon its face or end, and with these teeth is engaged 95 a bevel pinion M' secured to a shaft M, which also carries the drive-wheel M², adapted to engage and rotate the note-disk. The winding device for the spring consists of a large gear-wheel L³ secured to the shaft L⁴ of the 100 spring drum and meshing with a pinion N' on the winding shaft N. This shaft also carries a ratchet N² normally engaged by a retaining pawl O, fulcrumed at O'. Instead of being spring-pressed, according to the usual 105 construction, this pawl is operatively connected with an arm N³ mounted on said shaft and having a slot N⁴ into which extends a pin O² on the retaining pawl. Thus, when starting to wind the spring, the arm N³, being in 110

frictional engagement with the shaft or the ratchet by means of a pin N^5 , will swing the pawl O away from the ratchet N^2 , and owing to this distinctive feature the disagreeable noise commonly produced when winding spring motors will be avoided. At the same time, however, as soon as the spring winding operation is stopped, the slight backward rotation given to the winding-shaft by the tension of the spring will cause the retaining pawl to be swung back into engagement with the ratchet-wheel.

The motor or driving mechanism arrangement hereinbefore described is exceedingly simple, and its operation is practically the same, whether the motor is used to drive a note-disk or a talking machine record. In either event, the same starting and stopping mechanism is used and the same speed regulating mechanism. It will be understood, of course, that the clutch section G' of the shaft is exposed when the note disk is removed from the machine, and that this clutch section forms a carrier for the supporting plate F .

The form of my invention illustrated by Figs. 4 to 7 inclusive differs from the one first described, chiefly by the fact that provision is made for driving the music disk from the center instead of peripherally and also in the details of the stopping and starting mechanism and the speed governor.

The rotary supporting plate 1 has a pin 2 to center the record and is provided with a downwardly projecting socket 3, preferably tapered as shown, which is adapted to receive a corresponding projection 4 upon the shaft 5, thus forming a friction clutch. The shaft 5 carries the pinion 6 and the worm-wheel 7, which latter is in driving engagement with the worm 8 on the shaft 9 of the governor 10. Any suitable governor may be employed. The particular one illustrated comprises an arm secured to the shaft 9 and pivotally carrying at its ends the governor blades 10 under the influence of springs 10^a.

On the shaft 9 is mounted a projection 9^a adapted to collide with the arresting device as hereinafter explained. The pinion 6 is driven from a gear-wheel 11 mounted on a shaft 12 which also carries a pinion 13. This latter pinion is in mesh with a gear-wheel 14 on a shaft 15, which also carries another gear-wheel 16. Pinion 16 is in engagement with the gear-wheel 17 on the drum 18. This drum contains the customary spring, one end of which is secured to said drum and the other to the shaft 19, on which the drum is loosely mounted.

The winding device comprises a large gear-wheel 20 secured to the shaft 19, and engaged by a pinion 21 on a winding-shaft 22. This shaft has secured to it rigidly a ratchet-wheel 23 and a pin 24, which latter holds an arm 25 in frictional engagement

with sufficient force to cause such arm to partly follow the winding-shaft in its rotation. The arm 25 has a slot 25^a which receives a pin 26^a projecting from the retaining pawl 26. Thus, when the operator starts winding the arm 25 will throw the pawl 26 away from the ratchet-wheel 23, so that the clicking noise caused by the pawl sliding over the ratchet teeth will be avoided. As soon as the operator releases the key used for turning the winding-shaft, the arm 25 will swing the pawl 26 inward to again engage the ratchet-wheel 23. This winding device is the same as has been described with reference to the first form of my invention.

The upper end of the shaft 15 carries a support 27 for the note-disk, said support being provided with one or two eccentric pins 27^a adapted to engage corresponding holes in the note-disk and to drive the same.

Two starting devices are preferably provided, either one of which is adapted to coöperate with the arm 9^a. The starting device which is generally employed when the device is used as a music box comprises a lever 28 fulcrumed at 29, and adapted to project into the path of the arm 9^a, as shown in Fig. 7, the lever being normally held in such position by a spring. This lever is provided with an arm 28^a adapted to engage a portion of the drum 18, and to fall into a recess of said drum at a predetermined point. This construction is so well known that I have not deemed it necessary to illustrate the details thereof. It will be understood that during the greater portion of the drum's revolution the projection 28^a is swung so as to release the arm 9^a, but at a point which corresponds to the end of a piece, the projection 28^a will drop into the recess of the drum and thus bring about the stopping of the motor. In order to start the motor in this case a sliding rod 30 is employed, the end of which coöperates with an inclined surface 28^b of the lever 28.

When the apparatus is used as a talking machine, it is necessary that there should be a possibility of stopping the motor at any point. For this purpose a starting rod 31 is employed, having an end portion 31^a adapted to project into the path of the arm 9^a when such rod 31 is moved inward. It will be understood that during this use of the machine the rod 30 would be kept in its outer position so as to throw the lever 28 permanently out of action.

The speed may be regulated by means of an elastic brake 32 which is carried by an arm 33, fulcrumed at 34, and operated by means of a lever 35. This brake is adapted to swing against a spring-pressed collar 36, and by giving the lever 35 a greater or smaller throw the action of the brake and consequently the speed of the motor, may be regulated.

Various modifications may be made without departing from the nature of my invention.

I claim as my invention:

- 5 In a music box, a governor shaft, a governor carried thereby a vertical shaft in direct driving connection with the governor shaft, a holder for a note-sheet, and driving means for such sheet, said driving means being
- 10 operatively connected with the said vertical shaft, and a removable support for a talking

machine record, carried by the upper end of said vertical shaft at a level above the note-sheet holder.

In testimony whereof, I have signed my 15 name to this specification in the presence of two subscribing witnesses.

ERNST PAUL RIESSNER.
